UNITED STATES PATENT OFFICE

WILLIAM H. DAY, OF EAST HAVEN, CONNECTICUT, ASSIGNOR, BY MESNE ASSIGNMENTS,
TO REMINGTON RAND INC., OF NEW YORK, N. Y., A CORPORATION OF DELAWARE

INDEX OR FILE

Application filed March 7, 1925. Serial No. 13,820.

This invention relates to indexes or files, and more particularly to a device of this character, in which a base member or carrier is employed to carry or support a plurality of reference members, such as cards or the like, containing reference material. In the embodiment shown, the supporting member is in the form of a shallow tray or drawer, designed to be used in a file cabinet, but it is understood that in some of its aspects the invention will not be limited to the details shown, nor to the use of the same as described. Preferably the drawer or tray, or other card carrying device, is made of sheet metal. The drawer shown is provided with means to mount a plurality of index cards, such as are shown in the patent to Irving Fisher, No. 1,048,056 granted December 24, 1912, but should not necessarily be limited to use with such type of cards. Devices of this character when used as a tray or drawer for an index cabinet, are usually provided with a handle or drawer pull, which is secured to the front wall of the same. When constructed of sheet metal, the front wall becomes weakened and occasionally distorted under the constant strain, due to the pull exerted upon the handle. My invention, therefore, contemplates a drawer front structure which will obviate this tendency to distort, by the provision of a more rigid construction for a drawer or tray at this point. One object of my invention is to provide an improved supporting member or drawer to carry the reference members in a convenient and suitable manner so that the same will be protected against undue wear, and will at the same time be readily accessible. Another object of my invention is to provide a drawer for an index or file, in which the index members may be retained in proper position. A still further object of my invention is to provide a drawer or tray having an improved form of construction at the front face thereof, which will obviate any tendency of the same to become weakened or distorted under continuous use. A still further object of my invention is to provide a facing plate for a drawer of the

character described, which plate may be applied to the drawer in such a way that a pocket for the drawer label or the like, will be provided.

Generally speaking, my invention contemplates the provision of an improved drawer of this type made from one piece of sheet metal, and of such construction that it will be strong and durable and yet light in weight and pleasing in appearance as well as inexpensive to manufacture.

To these and other ends, the invention consists in the novel features and combination of parts to be hereinafter described and claimed.

In the accompanying drawings:

Fig. 1 is a top plan view of an index card supporting member in the form of a drawer or tray, embodying the features of this invention;

Fig. 2 is a front elevation of the same;

Fig. 3 is a top plan view of the front portion of the drawer on an enlarged scale, without the index cards;

Fig. 4 is an enlarged section on line 4—4 of Fig. 1, through the front portion of the drawer with the cards removed;

Fig. 5 is an enlarged section on line 5—5 of Fig. 1, through the front portion of the drawer, with the cards removed;

Fig. 6 is a front elevational view of the drawer with the outer front plate removed;

Fig. 7 is a partial section through the front of the drawer on line 7—7 of Fig. 2, looking in the direction of the arrows;

Fig. 8 is a rear view of the front plate member, looking into the same through the open space at the rear;

Fig. 9 is a section through the drawer on line 9—9 of Fig. 3, looking in the direction of the arrows, and

Fig. 10 is a longitudinal section through a drawer having a slightly modified form of outer front plate.

For illustrating the features of my invention, I have selected and shown a support or base member, for reference cards or the like, in the form of a drawer 10, formed from a single sheet of metal suitably shaped to provide the desirable depth. This drawer has a

83

85

90

100

bottom portion 11, which when in use, is substantially horizontally disposed. The material forming this bottom portion is bent angularly upward at each side, as at 12 and 13, then outwardly, as at 14 and 15, then vertically downwardly to provide side faces 16 and 17. The edges are then turned backwardly toward and in abutment with the drawer bottom, as at 18 and 19, and are depressed 10 slightly below the drawer bottom, thereby forming runways upon which the drawer will slide upon a support. The front portion of the drawer body as shown in the drawings is curved upwardly as at 20, and then abruptly 15 bent downwardly as at 21 to form a front face member for the drawer. The rear portion of the drawer body is also curved upwardly as at 22, and the edge portion thereof is bent back upon itself as at 23, in order 20 to stiffen the drawer crosswise at this point. Grooves 24 and 25 extend substantially the entire length of the drawer body to assist the box like side portions in stiffening the drawer lengthwise.

25 An index card retaining strip 26 is mounted lengthwise through the center of the drawer. This retaining strip is provided with outwardly directed flanges 27 and 28 at its side edges, which are adapted to engage tongues 30 29 of the type of index cards described in the Fisher patent, above mentioned.

A pair of bails 30 and 31 are provided, which are hingedly secured to the drawer bottom by means of supporting members 32. 35 The supporting members 32 are preferably spot welded to the drawer bottom, as at 33, and are located closely adjacent the angularly extending sides 12 and 13. These bails assist the index card retaining strip 26 in properly 40 retaining the index cards 34 within the drawer by bearing upon the upper edges thereof and urging the same downwardly by gravity.

A pair of ears 35 and 36, in this instance struck up from the material forming the 45 drawer bottom, are provided at the forward end of the drawer, and are so located that they will engage an edge of the forwardmost card in order that the cards will not slip out of the drawer during the movement thereof 50 in and out of the cabinet or other storage device.

Label card retaining ears 37 and 38 are struck outwardly from the vertical front plate 21 of the drawer, and a series of hook-like members 39 are struck out from the same plate, being directed upwardly to form outer front plate engaging fingers. The side vertical portions 16 and 17 are extended beyond the drawer at the front end, and are 60 formed in the shape of ears 40, which are bent over the front face of the plate 21, and brace the same at this point.

The outer front plate 41 is also formed from sheet metal, and comprises a front face portion 42, having a rearwardly di-

rected upper edge flange portion 43, and a rearwardly directed lower flange portion 44, which is extended beyond the lower edge of the plate 21, and along the bottom of the drawer, as at 45 and 46, respectively, and at 70 46 it is preferably spot welded to the same. The portion 43 of this outer front plate is provided with spaced apart label receiving openings 47 and 48 forming passageways, through which suitable labels 52 may be inserted into the space between the plates 41 and 21. In the front face portion 42 of this plate, there are provided a pair of openings or windows 49 and 50, through which the insignia upon the labels may be observed. An inwardly directed flange 51 is provided about each of the windows 49 and 50. This flange somewhat restricts the space between the outer plate 41 and the front plate 21 of the drawer, so that the label card 52 will be somewhat supported thereby, and by extending to overlap the ears 37 and 38 assists the same in retaining the label card in proper position transversely of the drawer and in back of the windows 49 and 50, as well as causing the surface of the label to be below the surface of the outer front plate so that the same will be protected against becoming soiled by handling. The ends of the front portion 42 are bent inwardly as at 53 and 54, and abut the drawer at each corner, to close the space between the plates 41 and 21 at the ends and somewhat vertically stiffen the outer plate member. These end closure portions also assist in locating the front plate 41 transversely upon the drawer. A handle member 55 is provided which passes through the front portion 42 and is riveted over on the inside as at 56.

105 The rearwardly directed flange portion 43 is slightly depressed at its rear edge and abuts the front end of the drawer bottom in this instance, as well as the upper edge of the inner plate 21. The hook like members 39 engage the edge of the flange portions 43 and retain the same in close abutment with the front of the drawer, thereby securing the outer front plate to the drawer bottom at this point. The rearwardly directed lower flange portion 44 closes the bottom of the space or recess between the plates 41 and 21 to form a bottom for the label card pockets. This flange portion 44 continues rearwardly until it is in engagement with the drawer bottom, and is at this point secured thereto. In this manner, the inner front plate 21 is substantially enveloped by the outer plate 41, and the space or recess therebetween is substantially enclosed.

110 120 125 The modification shown in Fig. 10 consists of a somewhat differently constructed outer front plate 60, and there is provision of separate card retaining ears 61. In this construction the front face portion 62 is extended 130

upwardly beyond the upper front edge of the drawer a desirable distance, then bent rearwardly as at 63, and then downwardly as at 64 where the edge of the material is engaged by the ears 39. A slot or slots 65 is provided in the portion 63, through which label cards may be inserted into the recess or space between the plate 60 and the inner front plate 21. In all other features this outer front plate is similar to the previously described one, as is also the body portion and inner front plate construction of the drawer, with the exception that separate card retaining ears 61 are provided which are spot welded or otherwise secured in proper position upon the drawer bottom.

One of the advantages of the drawer construction above described, is that a drawer body of given depth is adapted to be used in cabinets or the like, having the distance between the drawer supporting partitions either the same or greater than the depth of the drawer body. This is made possible by the use of a front plate of such dimensions that the space between the partitions will be closed by this plate at the front of the cabinet when the drawer is within the same.

From the above, it is obvious that this invention has provided a light yet rigid and durable index card supporting member, easily and inexpensively manufactured from sheet metal. The structure described whereby the outer front plate portions 43 engage the ears 39 of the inner front plate, and the securing of the portion 46 to the undersurface of the drawer bottom causes the strain, due to the pull upon the handle 55, to be distributed directly to the drawer body and not upon the inner face plate 21. The inner face plate 21 is braced by the side member ears 40, and being vertically disposed relatively to the drawer body strengthens the drawer at the front portion against twisting or other distortion. The label locating ears 37 and 38, and the flanges 51 to the openings 49 and 50, with the adjacent front surface of the inner plate 21, form spaced apart label card pockets into which label cards 52 are readily inserted from the top through the passageways 47 and 48, respectively, and within which the labels will be retained in proper position relatively to the windows 49 and 50. The inner and outer front portions of the drawer cooperate when constructed as above described to form stress reducing means for the front portion of the drawer.

While I have shown and described a preferred embodiment of my invention, it is to be understood that the same is not limited in all of its details but is capable of many modifications and variations thereof which will lie within the spirit of the invention and the scope of the appended claims.

What I claim is:

1. In an index or file, a facing member for

a drawer or the like, including an upper flange portion engageable with a portion of the front of said drawer, a front plate portion having openings therein, and spaced by said flange portion from the front of said drawer and a lower flange portion extending beneath said drawer and secured thereto, said first mentioned flange portion being provided with a drawer label receiving opening through which a label or the like may be inserted so as to be observable through the openings in said front plate portion. 70

2. A facing member for the front of a drawer or the like, including a front plate having a flange portion engageable with a portion of said drawer front adjacent its upper edge, and another flange portion extending rearwardly over a surface of said drawer bottom and secured thereto, said front plate having openings to display a drawer label or the like, said first mentioned flange portion having openings to allow the insertion of a drawer label to the rear of said front plate. 80

3. In an index or file, the combination of a drawer having a bottom, said bottom rising upwardly at the front end thereof to form an upper front edge for said drawer, a member co-extensive with the width of said drawer disposed across the front thereof to form a front face for said drawer attached to said bottom, and another member in front of and spaced from said first mentioned member whereby a recess is formed therebetween, said second mentioned member substantially 95 enveloping said first mentioned member and secured to said bottom at the upper and under surface thereof. 100

4. In a drawer for an index or file, an inner front face member and an outer front face member, said members being spaced apart to provide a label receiving recess therebetween, an opening in said outer member through which the label may be observed, pocket forming means on said inner member for retaining the label in position relatively to said opening and against transverse displacement therefrom. 105

5. In a drawer for an index or file, an inner front face member and an outer front face member, said members being spaced apart to provide a label receiving recess therebetween, an opening in said outer member through which the label may be observed, means on said inner member for retaining the label in 115 position relatively to said opening, and against transverse displacement therefrom, and means on said outer member restricting the recess at the rear of said opening to insure the action of said label retaining means. 120

6. In a drawer for an index or file, an inner front face member and an outer front face member, said members being spaced apart to provide a label receiving recess therebetween, an opening in said outer member through 130

- which the label may be observed, pocket forming projections on said inner member for retaining the label in position relatively to said opening and against transverse displacement therefrom, one of said members being formed to provide a downwardly directed passageway communicating with the pocket therebetween for the insertion of a label card therethrough and into said recess.
10. 7. A drawer for an index or file, having a bottom formed with an inner front face member, and an outer front face member having marginal flanges engaging said inner front face member and spacing said outer face member from said inner face member, means uniting said outer face member with said inner face member, whereby said outer and inner face members in said spaced relation provide a tubular drawer front and have stress reducing cooperation.
8. A drawer for an index or file having an inner front face member, an outer front face member, means mounting said outer front face member in spaced parallel relation with said inner front face member, and cooperating means on said inner and outer face members for receiving and retaining a label between said members and displaying said label through an opening in said outer face member.
9. In a drawer for an index or file, a bottom having an inner front face member, an outer front face member having flanges engaging and spacing said outer face member from said inner face member, and means on said outer face member extending past said inner face member and secured to and engaging said bottom in angular relation, said flanges, means and face members having stress reducing cooperation.
10. In a drawer for an index or file, a bottom having the forward end inclined upwardly, an inner front face member secured to said bottom at its upper edge, an outer front face member having marginal flanges engaging the edge portions of said inner face member and spacing said outer face member therefrom, an angular extension on said outer face member secured to said bottom, and means preventing lateral displacement of one face member relative to the other, said face members having stress reducing cooperation.

In testimony whereof, I have hereunto set my hand this 5th day of March, 1925.

WILLIAM H. DAY.

CERTIFICATE OF CORRECTION.

Patent No. 1,837,019.

Granted December 15, 1931, to

WILLIAM H. DAY.

It is hereby certified that error appears in the printed specification of the above numbered patent requiring correction as follows: Page 4, line 9, claim 6, for the word "recess" read pocket; and that the said Letters Patent should be read with this correction therein that the same may conform to the record of the case in the Patent Office.

Signed and sealed this 9th day of February, A. D. 1932.
